CONTINUOUS ROTARY NOTE PADS

Ethan Weckesser, Chicago, Ill.

Application June 7, 1954, Serial No. 434,889

1 Claim. (Cl. 281—8)

This invention relates to note pads and more particularly to continuous rotary note pads. One object is to provide a rotary note pad including a base portion horizontally disposed at the lowest point of the pad, the base adapted to rest directly upon a support and directly receiving and supporting the writing paper at the point of writing thus providing that stability required for the writing operation.

A further object is to provide a rotary note pad having guide means for keeping the writing paper perfectly straight in its movement along the base, means being provided also for paper movement back and forth, as desired, to permit inspection of anything previously written.

A further object is to provide improved means for so mounting the rollers that they are easily movable, the rollers or shafts associated with sleeves constantly under tension thus preventing slack in the paper at all times.

Other and further objects of the invention will be obvious from the following description and claims and are illustrated in the accompanying drawing which, by way of illustration, show a preferred embodiment of what I at present consider to be the best mode contemplated for applying these principles. Other embodiments of the invention involving the same or equivalent principles may be used and structural changes made as desired by those skilled in the art without departing from the present invention and the purview of the appended claim.

In the drawing:

Fig. 1 is a side elevational view of a continuous rotary note pad embodying the instant invention.

Fig. 2 is a top plan view of the same.

Fig. 3 is an enlarged fragmentary view of the pad, partly in section, showing an end shaft, sleeve and associated features.

Fig. 4 is an end view, also partly in section, showing an end bearing and associated features, and,

Fig. 5 is a vertical sectional view showing one of the spindles and allied features.

The reference numeral 1 denotes the elongated base at each end of which is a pair of spaced upstanding ears 2, 3, each pair of ears having welded or otherwise secured thereto bearings 3a, the bearings at each end of said base operatively supporting a rotary split shaft 4, tubular and of greater diameter throughout its length than a perforation 5 in one ear of each pair of ears,

2

the shaft end contiguous to said perforation 5, however, being formed contracted and with a perforation 6 through which a crimp 7 in one side of the U-shaped spring 8 yieldingly extends and contacts a bearing 3a, said spring 5 disposed within shaft 4 and its closed end remote from the adjacent shaft end, the opposite end of said shaft extending through and beyond an ear 2 and having fast upon its outer end the knob or handle 9.

Encompassing said shaft 4 but spaced slightly therefrom is the split or slit sleeve 10 extending from bearing to bearing, square in cross section, and formed with a longitudinal lip 11, Fig. 3, disposed in the slit in said shaft 4, said lip 11 permitting only a slightly relative rotary movement of shaft 4 and sleeve 10. The purpose 15 of the spring 8 is to yieldingly permit withdrawal of the shaft from the sleeve when desired and to facilitate assembly of the device.

Rising from the base 1 between the ears at each end 20 having a shaft 15 upon which are pivotally mounted the extensions 16 of a friction plate 17 engaged by a spring 18 one end of which is secured to said extension 16 and the opposite end to a bearing 3a to yieldingly retain said friction plate in engagement with a roll of paper 19 secured at its ends to or between the shaft 4 and sleeve 10, the paper from said roll passing beneath a guide roller 14 lengthwise of said base and beneath the opposite guide roller and in like manner secured to the shaft 4 and sleeve 10 at the opposite end of the device, the 30 paper thus moving longitudinally of the base in continuity therewith to provide a firm writing surface.

In operation one roll of paper may be wound about a sleeve 10 by rotation of one knob 9 and unwound 35 from the opposite sleeve, the pressure of the plates 17 keeping the paper taut and straight in its movements over the base. When one knob 9 is rotated the round shaft 4 engages the lip 11 of a sleeve 10 and rotates same to wind the paper thereupon from one end of the device to the other, and winding the paper in the opposite 40 direction by the other knob 9 will expose and bring to view matter already written but obscured by the forward movement of the paper.

What is claimed is:

In a continuous rotary note pad, a base, rotary manually actuated drive shafts operatively arranged upon opposite ends of said base, sleeves encompassing said shafts and driven thereby, said sleeves having fast thereto the ends of a roll of paper to be unwound from one sleeve and wound upon the other sleeve as said shafts are selectively rotated, lugs at the ends of said base, guide rollers for the paper carried by said lugs adjacent said sleeves, friction plates pivotally carried by said base engaging the paper roll, said friction plates having extensions, and spring-pressure means carried by said friction plate extensions exerting pressure upon the paper roll.
